UNITED STATES PATENT OFFICE.

FRANK E. DODGE AND NORMAN M. LOOMIS, OF HARTFORD, CONNECTICUT.

ELECTRIC COIN-CONTROLLED DEVICE.

1,074,496.

Specification of Letters Patent. Patented Sept. 30, 1913.

Application filed August 30, 1912. Serial No. 717,898.

To all whom it may concern:

Be it known that we, FRANK E. Dodge and NORMAN M. LOOMIS, citizens of the United States, residing at Hartford, in the 5 county of Hartford and State of Connecticut, have invented certain new and useful Improvements in Electric Coin-Controlled Devices, of which the following is a specification.

10 Our invention relates to improvements in electric coin controlled devices, and the object of our improvements is simplicity and economy in construction and convenience and efficiency in use.

15 In the accompanying drawing: Figure 1 is a front elevation of our electric coin controlled device. Fig. 2 is a rear elevation of the same, the casing being in part broken away. Fig. 3 is an end elevation of the 20 same. Fig. 4 is a view corresponding to Fig. 2 and on an enlarged scale of certain parts shown in the said figure. Fig. 5 is a sectional view on the line *x-x* of Fig. 4. Fig. 6 is a view corresponding to Fig. 3 of 25 certain parts shown in the said figure. Fig. 7 is a view corresponding to Fig. 6 and on a still further enlarged scale of the magnet and adjacent parts. Fig. 8 is a front elevation of the same. Fig. 9 is a rear elevation 30 of certain parts shown in Figs. 2 and 4 and on the same scale as Figs. 7 and 8. Fig. 10 is a sectional view of the goods wheel on the line *y-y* of Fig. 1. Fig. 11 is a side elevation, on an enlarged scale, of a coin and 35 part of the coin chute. Fig. 12 is a sectional view of the same on the line *z-z* of Fig. 11.

Our electric coin controlled device A comprises a casing B having a coin slot 15 for 40 admitting a coin C, a delivery outlet 16 for the delivery of a goods unit D responsive to the insertion of a coin C in the said coin slot 15 and mechanism E released by the said coin C and operative to effect such delivery of the said goods unit D.

The casing B comprises a base 17, a front wall 18, a rear wall 19, and lateral walls 20 extending upwardly therefrom and meeting at the top. The upper portions of the front 50 and rear walls 18 and 19 are circular and concentric with the axis of the driving shaft F, and the said upper portion of the front wall 18 has a glass door 21 and the lateral walls 20 which connect the said upper portions combine to form a cylindrical chamber 28 for the upper portion of the casing B

and which is correspondingly concentric with the said axis of the driving shaft F.

A pair of standards G are suitably supported from the base 17, as shown being 60 secured to a platform 22 which is part of the said base 17, and which standards are provided at the upper ends with bearings 23 for the main shaft F, the rear standard G and bearing 23 being adjacent the rear 65 wall 19 and the front standard G and bearing 23 being located approximately in the middle of the length of the casing B.

A goods delivery chute 24 is provided in the casing B connecting the goods delivery 70 opening or mouth 16 with the delivery mechanism of the operating mechanism E to be described and a coin chute 25 delivers the coin C from the coin slot 15 to the said operating mechanism E.

75 The driving shaft F is suitably supported in a horizontal position by the bearings 23 and comprises a portion 26 between the bearings 23 on which is mounted a driving gear 27 adjacent the front bearing 23 and a controlling wheel H intermediate the said driving gear 27 and the rear bearing 23. A portion 29 of the said driving shaft F overhangs the front bearing 23 and supports a 80 goods wheel I.

85 The goods wheel I comprises a central hub portion 30 suitable for being mounted on the shaft F and for supporting a spider 31, and which spider supports on the outer periphery an annular goods rim section 34 90 which is divided by radial partitions 32 into a plurality of goods receptacles 33. The bottom of the goods receptacles or pockets 33 is closed by a fixed closure in the form of a shell mounted on the radial arms of the 95 spider 31 and the rear end thereof is also closed by a fixed closure by means of a back plate or disk 35. The front edges of the partition walls 32 operate in close proximity to the glass door 21 of the front wall 100 18 so that the said glass plate serves as a closure for the front ends of the goods receptacles or pockets 33.

105 Within the upper cylindrical inclosure 28 mentioned and concentric therewith is a cylindrical shell 80 that is positioned in proximity to the outer ends of the partition walls 32 and serves as a closure of the outer ends of the goods pockets 33, and serves particularly in the case of the pockets 33 110 in the lower positions as a track to partially support the goods D and retain the same in

the said pockets. At the extreme lowermost position the said track 80 is interrupted to provide a delivery opening 41 which is of sufficient size to permit the passage of a goods unit D from the lowermost pocket 33 when in registration therewith. The said delivery opening 41 constitutes the inlet for the goods units D to the goods delivery chute 24 leading to the goods delivery outlet or mouth 16.

The chute 25 is suitably curved to deliver the coin C from the coin slot 15 which is preferably at the front and upper part of the casing B to the coin operated or check mechanism J and as the said chute is preferably made of metal, the same is provided intermediate the length with an insulating section 42 whereby the lower portion 43 thereof which constitutes part of the check mechanism proper is insulated from the upper portion. A coin delivery chute 44 in continuation of the chute 25 and the said lower portion 43 thereof delivers the coin C when released by the check mechanism J in a manner to be described to a coin chamber K in the lower part of the base 17 and which has a door 45 at the front controlled by a lock and key. The upper portion of the chute 25, particularly the winding portion thereof, is formed by a pair of laterally disposed channelled members 51 having shallow channels to fit the edges of the coin C and having the opposed edges separated by an open space 52 through which a coin that is of smaller diameter than the coin for which the chute 25 is designed will pass and fall to the base 17 instead of following the route of the chute which the proper coin will follow.

The operating mechanism E comprises the check mechanism J and goods delivery mechanism L, the operation of which mechanisms is controlled by the controlling wheel H when released by the coin C. The said controlling wheel H is mounted on the shaft F and has an annular rim 46 which is provided on the rear face with a plurality of projections or pins 47 that are parallel with the axis and serve as stops and constitute the controlling means proper, and which stops correspond in number to the number of goods pockets 33.

The movement of the controlling wheel H as viewed in Figs. 4 and 9 is counter-clockwise, and the same is operatively connected through gearing M comprising the gear wheel 27 on the shaft F with a spring motor N which tends to impart such movement thereto and the same is normally held against such movement by the engaging nose 48 of the armature 49 of a magnet O engaged with one of the said stops 47. A spring latch 50 engages with another of the stops 47 and prevents retrograde movement thereof, particularly any rebounding inci-

dental to the shock from sudden stopping of the movement of the mechanism by the action of the nose 48 engaged with a stop 47. The spring latch 50 is an elongated strip pivoted at about the middle by means of a pivot pin 52 secured to the rear standard G, has the upper end 53 suitably shaped to have one edge engage with one of the stops 47 to prevent clockwise movement and having the body portion angularly disposed relatively to the stops 47 so as to have sliding engagement with the free ends thereof and to be pushed to one side when the controlling wheel H is moved in the proper counter-clockwise direction and to permit such movement, the spring 54 engaged with the lower end of the latch 50 operating to hold the upper end 53 thereof in engaging position. The magnet O comprises the electromagnet 55, which is suitably supported from the frame G, the armature 49 that is pivotally supported by the lower end, the spring 56 that tends to hold the armature 49 away from the poles of the magnet proper 55, and the adjustable armature stop 57 and is positioned so that the nose 48 of the armature 49 is in engagement with one of the stops 47, and serves to hold the controlling wheel H and the goods wheel I against movement by the motor N.

In order to relieve the pivotal bearings for the armature 49 from the duty of directly holding the stop or pin 47 as described we provide a back stop or backing 58 in the form of a fixed stop that is engaged with the lateral edge 59 of the nose 48 when the same is in normal position of engagement with the stop or pin 47, which backing 58 operates to take the direct strain in such holding position. When the magnet 55 is energized the same draws the armature 49 and disengages the nose 48 from the pin with which the same is engaged and when the magnet is deenergized the spring 56 moves the armature 49 and nose 48 back to position of engagement.

The coin tripping mechanism comprises a tripping arm 60 comprising an elongated and generally horizontal arm pivotally mounted by means of a pivot pin 61 at about the middle of its length having the inner end 65 normally depressed by means of a spring 62 and provided at the outer end with a contact arm 63 that is normally adjacent the coin chute 43 and separated therefrom by a space so as to provide a gap 64. The chute 43 and contact arm 63 are in the electric circuit with the coils of the magnet 55 and which may be supplied with current by means of batteries, transformer, or other convenient means, so that when the gap 64 is bridged by the coin C the electric circuit is closed and the magnet 55 is energized, resulting in releasing the controlling wheel H and goods wheel I and permitting a move-

ment thereof responsive to the impulse of the motor N. The pivot pin 61 is mounted on the side of a bearing plate 66 having a bearing surface 67 opposed to the said arm 60 and the said arm 60 is held in bearing engagement with the said surface 67 by the head of the said pivot pin 61 and is positively positioned thereby when at rest and suitably guided during its limited reciprocating movement. The said bearing plate 66 and chute 43 are supported by an insulating block 68 so that the same and the arm 60 are normally, electrically disconnected from the other parts of the frame and mechanism.

The inner end 65 of the arm 60 is normally positioned adjacent and separated from the rear face of the annular rim 46 of the controlling wheel H and overhangs one of the pins 47 and is provided on the under side with an inclined bearing edge 69 which is adjacent the said pin 47 and normally separated therefrom by a space and is suitable when the controlling wheel H is moved in the manner described to ride on the said pin 47 and be lifted thereby.

The upward movement of the inner end 65 described is accompanied by a dropping of the outer end of the arm 60 and of the contact arm 63, resulting in separating the same farther from the chute 43 or opening of the gap 64 sufficiently to permit the coin C to drop by way of the coin delivery chute 44 to the coin chamber K. The dropping of the coin C from the gap 64 results in opening the electric circuit and releasing the hold of the magnet 55 on the armature 49, whereupon the nose 48 will momentarily ride on the rear end of the pin 47 with which it was previously engaged until the said pin has been moved sufficiently to clear the said nose 48 whereupon the said nose 48 will be moved forward in position to engage with the next pin 47. After the inner tripping end 65 of the tripping arm 60 has passed over the pin 47 with which it was engaged the same will be dropped to normal position by the spring 62. A stop 70 limits the downward movement of the inner end of the tripping arm 60. A wire 71 connects the bearing plate 66 with the tripping arm 60, relieving the pivotal connection electrically.

The arms of the spider 31 and the hub portion thereof are positioned at the rear end of the goods wheel I so that a free space is provided within the cylindrical shell portion 34 of the goods wheel I in which the forward end 29 of the shaft F projects. In this space we house an advertising device comprising a hub and spider P which is freely mounted on the shaft end 29 and is provided on the front end with a disk 81 on the front face of which the desired advertising matter is placed, and the same is main-

tained in proper and definite position regardless of the movements of the shaft F or 29 by means of a counter weight 72 fixed to the lower portion of the disk 81 or in any other suitable manner.

As described, the insertion of the coin C in the coin slot 15 operates the check mechanism J by closing the electric circuit for the magnet 55 which operates to free the controlling wheel H and permit the operation of the goods delivery mechanism L and each movement responsive to the insertion of a coin corresponds to the spacing between adjacent pins 47. As the partition walls 32 of the goods pockets 33 are radial the said walls are divergent when in position for delivery of the goods unit D through the inlet 41 to the goods delivery chute 24 and permit the free exit of the said goods unit D.

The goods wheel I is made of metal, being preferably an aluminum casting, and is removably secured on the shaft F in an ordinary manner, as by a set screw 73, so that the same may be readily removed from the shaft as a unit and cleaned and sterilized and maintained in a sanitary condition, which is desirable in case the goods units supplied are food products. The casing B is formed generally after the manner of a clock case, and the glass door 21 is mounted in a manner similar to the glass door of clocks, being hinged at one side and latched at the other side and the latched side is provided with a lock.

We claim as our invention:

1. A coin controlled device comprising a shaft, a motor tending to turn the said shaft, a controlling wheel mounted on the said shaft, and having a plurality of pins and means responsive to the insertion of a coin in the said device for engaging and disengaging the said pins and thereby controlling the movement of the said shaft, the said means comprising holding means engaged with one of the said pins and a tripping arm, pivotally supported, having the outer end suitably positioned to engage with a coin inserted in the said device and the inner end provided with a tripping nose and suitably positioned to be engaged with another of the said pins responsive to a turning movement of the said controlling wheel.

2. A coin controlled device comprising a shaft, a motor tending to turn the said shaft, a controlling wheel mounted on the said shaft, and having a plurality of pins, and means responsive to the insertion of a coin in the said device for engaging and disengaging the said pins and thereby controlling the movement of the said shaft, the said means comprising holding means engaged with one of the said pins and a tripping arm, pivotally supported, having the outer end suitably positioned to engage with a coin inserted in the said device and the in-

100

105

110

115

120

125

130

ner end provided with a tripping nose and suitably positioned to be engaged with another of the said pins responsive to a turning movement of the said controlling wheel, 5 the said outer end being provided with contact fingers, and a coin chute having a closed inner wall and an outer wall provided with an opening, and the said contact fingers being positioned in the said 10 opening.

3. In a coin controlled device comprising a shaft, a motor connected thereto, and a controlling wheel mounted on the said shaft, and having a plurality of pins on one face, 15 a coin chute and a tripping arm, holding means operative normally to hold the said controlling wheel in opposition to the said motor, the said tripping arm being pivotally supported by the middle portion, the 20 inner end of the said tripping arm having a tripping nose positioned normally adjacent one of the said pins suitably to be tripped thereby responsive to a movement of the said wheel, contact fingers on the 25 outer end of the said tripping arm, the said chute having one closed wall and a wall opposite the said closed wall provided with an opening, the said contact fingers being positioned in the said opening and normally 30 separated from the said closed wall by a space suitable to be bridged by a coin, and the position of the pivotal support for the 35 said tripping arm being such relatively to the said chute that upon the tripping of the said tripping arm the said contact fingers will be moved away from the said closed wall so as to increase the extent of the said space suitably to permit the said coin to drop between the said contact fingers and 40 closed wall.

4. In a coin controlled device, a controlling wheel, a plurality of pins thereon, a motor tending to move the said wheel, a magnet having an armature, the said armature being pivotally mounted by one end, the other 45 end of the said armature being normally engaged with one of the said pins, and a backing engaged with the said other end and serving to positively position the same in the normal plane of movement, and means 50 for energizing the said magnet responsive to a coin inserted in the said device.

5. In a coin controlled device, a controlling wheel, a plurality of pins thereon, a motor, a magnet having an armature normally engaged with one of the said pins, 55 a tripping arm pivotally mounted, having a contact finger at the outer end, the inner end of the said arm being positioned adjacent another of the said pins and suitably 60 shaped to engage therewith and to be tripped thereby responsive to a movement of the said controlling wheel.

6. In a coin controlled device, a controlling wheel, a plurality of pins thereon, a 65 motor connected with the said controlling wheel, a magnet having an armature normally engaged with one of the said pins, a tripping lever having one end adjacent another of the said pins and a latch engaged with a third of the said pins, and means for energizing the said magnet responsive to a coin inserted in the said device. 70
